UNITED STATES PATENT OFFICE.

JUDSON C. NEYHART, OF WILLIAMSPORT, PENNSYLVANIA.

DESIGN FOR A GAME-BOARD.

SPECIFICATION forming part of Design No. 31,019, dated June 13, 1899.

Application filed May 18, 1899. Serial No. 717,365. Term of patent 7 years.

To all whom it may concern:

Be it known that I, JUDSON C. NEYHART, a citizen of the United States, residing at Williamsport, in the county of Lycoming and State 5 of Pennsylvania, have invented and produced a new and original Design for a Game-Board, of which the following is a specification.

This invention relates to a new and original design for a game-board; and it has for its object to provide a design of this character that shall be both useful and ornamental.

The leading feature of the design resides in a game-board provided upon its playing-surface with a rectangular field having two diagonally opposite corners truncated on parallel 15 lines and provided therein with a plurality of diagonal rows of perforations.

While the essential feature of the design resides in a rectangular field having the diagonal 20 rows of perforations and the diagonally opposite truncated corners, the invention also involves a minor feature, which is the game-board having within the rectangular field thereof a series of parallel right-angularly 25 crossing diagonal lines which intersect each other at the perforations and form the boundaries of rows of diamond-shaped figures.

In the drawings, Figure 1 is a plan view of a game-board embodying the herein-described 30 design. Fig. 2 is a cross-sectional view of the game-board.

Referring to the accompanying drawings, the numeral 1 designates a game-board provided with a flat playing-surface 2, having thereon a rectangular field 3. The rectangular field 3 is inclosed within marginal lines arranged at right angles to each other. The two diagonally opposite corners of said rectangular field 3 are truncated on the parallel 35 lines 4. The said rectangular field 3, having the diagonally opposite truncated corners 4, is provided therein with a plurality of diagonal rows of circular perforations or openings 40 and is also provided with a series of parallel diagonal lines 6, crossing at right angles and 45 intersecting each other at the perforations or holes 5. The right-angularly intersecting lines 6 form the boundaries of rows of diamond-shaped figures 7, which complete the design for the game-board. 50

What is claimed is—

The design for a game-board, herein shown and described.

In testimony that I claim the foregoing as my own I have hereto affixed my signature in 55 the presence of two witnesses.

JUDSON C. NEYHART.
